UNITED STATES PATENT OFFICE.

GEORGE M. DIEHL, OF WABASH, INDIANA, ASSIGNOR TO WARREN A. REED AND
BRADFORD W. BURNS, BOTH OF CHICAGO, ILLINOIS.

COIN-CONTROLLED CALENDAR.

Application filed December 16, 1921. Serial No. 522,772.

To all whom it may concern:

Be it known that I, GEORGE M. DIEHL, a citizen of the United States, residing at Wabash, in the county of Wabash and State 5 of Indiana, have invented a new and useful Coin-Controlled Calendar, of which the following is a specification.

The object of my invention is to make a coin depository comprising coin-controlled 10 calendar mechanism, the arrangement being such that by the insertion of a coin and the manipulation of an operating lever the calendar mechanism may be advanced step by step to indicate the date and also to indicate 15 the minimum number of coins deposited in the repository in relation to the calendar period.

The accompanying drawings illustrate my invention. Fig. 1 is a fragmentary elevation 20 in partial vertical section showing the coin-receiving mechanism and the operating lever; Fig. 2 a fragmentary elevation of the ratchet and pawl mechanism in initial position; Fig. 3 a view similar to Fig. 2 with 25 the parts moved to the end of an operating stroke; Fig. 4 a fragmentary elevation in partial vertical section showing the mechanism for the closing movement of the "month" wheel; Fig. 5 a fragmentary detail 30 of the "month" controlling mechanism; Fig. 6 a side elevation of the "month" controlling dial; Fig. 7 a plan of the mechanism with the repository casing in horizontal section; Fig. 8 a horizontal axial section; Fig. 9 a 35 front elevation with a portion of the face of the casing removed, and Fig. 10 a fragmentary vertical section showing the supplemental coin slot.

In the drawings, 20 indicates a suitable 40 closing casing having a primary coin-receiving slot 21 and associated guide 22; a supplemental coin-receiving slot 23 and associated guide 24; and a removable coin receptacle 25.

Aligned with the lower end of guide 22 is a coin-receiver 26 provided at its lower end with a finger 27 upon which the coin will primarily rest so long as it is retained in that position by swinging retaining finger 28 which is carried by shaft 29 journaled in a suitable frame 30. Opposing finger 28 is a finger 31 normally spaced from finger 28 by at least the thickness of the coin. The finger 28 is slotted, in alignment with finger

31, so that, in the absence of a coin, finger 55 31 can have no effect upon finger 28.

Finger 31 is part of a plate 32 which is slidably supported in slots 33 and 34 in frame 30 and may be reciprocated by means of a lever 35 which is projected through the 60 casing 20.

When a coin is deposited in slot 21 it drops upon shelf 27 and lies between the fingers 31 and 28. Manipulation of lever 35 will then swing finger 28 and cause movement of 65 two pawls 36 and 37 which are carried by arms 36' and 37' respectively, secured to shaft 29. These pawls, acting respectively upon the 14-tooth ratchet wheel 38 and the 31-tooth ratchet wheel 39 cause a one step 70 advancement of the week-day dial 40 and the number dial 41 so as to bring appropriate portions of the faces of said dials opposite the sight opening 42 of the casing. The number dial 41 is provided with a circular 75 series of numbers from 1 to 31 and the week-day dial is provided with two sets of week-day designations. I provide dial 40 with two sets of week-day designations merely be- 80 cause it is more convenient to form a 14- tooth ratchet wheel than a 7-tooth and permits a shorter operating stroke. Pawl 36 is so formed as to be incapable of driving ratchet wheel 38 more than one step, the pawl being curved, as clearly indicated in 85 Fig. 3, adjacent its active end, and consequently this pawl rides out of engagement with the ratchet wheel 38 during the final portion of the stroke of the pawl. The total possible movement of rock shaft 29 is enough 90 to advance the ratchet wheel 39 through four steps but such movement is normally restricted to a single step by means of a finger 37" carried by arm 37', and a shoulder 95 43 carried by an arm 44 hung upon pin 45 of frame 30 by means of a downwardly open slot 46 which permits ready removal without dismantling the structure as a whole. The finger 37" is slotted to receive, guide and support the end of arm 44.

Assuming that the apparatus has been properly set and started on the first of January, the 30th step of advancement of ratchet wheel 39 will bring a finger 47, which is formed integrally with the ratchet 105 wheel into engagement with a projection 48 on the lower edge of arm 44 and thus raise shoulder 43 so that pawl 37 might be ad-

vanced more than one step but, as January is a month having 31 days, such advancement is prevented by a finger 49 which overlies the circumference of a disk 50 (Fig.

5) the periphery of which is appropriately notched and, during the January period, presents an unnotched surface to block excessive movement of finger 49.

On the 31st actuation of ratchet wheel 39, 10 a cam 51 (Fig. 4), which is integral therewith has its drop-off brought into position to permit an arm 52, which rests on the periphery of the cam to drop and, though the medium of a finger 53, which is projected through a swinging arm 54, to permit spring 55 to draw arm 54 downwardly and cause the gravity pawl 56 carried by the arm, to act upon a ratchet wheel 57 and advance it one step. This ratchet wheel 57 15 is integral with disk 50 and is carried by a sleeve 58 journaled on the shaft 38', which connects ratchet wheel 38 and dial 40. The sleeve 58 serves as a bearing for the element 39—47—51. The advancement of ratchet wheel 57 brings a February notch of disk 50 into alinement with the path of movement of finger 49. Element 50 is divided into twenty-four equal angular spaces and ratchet wheel 57 is a 24-tooth ratchet. A 20 disk 50' is carried by sleeve 58 and carries month designations visible through the sight opening 42.

Advancement of element 50 just referred to brings a pawl 60, which is pivotally mounted on the element 50, so that its free end lies beneath a finger 61 carried by the arm 44 and on the actuation which corresponds with the 27th day of February a pin 62 (Fig. 5) carried by the ratchet wheel 39, engages said pawl and causes it to lift arm 44 so as to retract shoulder 43 from blocking position so that, on the actuation corresponding with the 28th of February, the finger 49 will enter the long February slot of element 50 and permit a swing of the actuating member 35 which will be sufficient to cause pawl 37 to move ratchet 39 through four spaces. This movement will, of course, move cam 51 enough to cause an actuation of ratchet wheel 57 by pawl 56, in the manner already described, as soon as finger 49 is retracted from the February slot of element 50.

At each angular portion of the element 50 which will lie opposite finger 49 on the last day of a thirty day month, the periphery of element 50 is provided with a shallow notch, as indicated in Fig. 6 at the

April, June, September and November positions, so that finger 49 will not be blocked until pawl 37 has been moved through a distance sufficient to advance ratchet wheel 39 through two spaces.

Reverse movement of the ratchets 38 and 65 57 are prevented by spring urged pawls 70

and 71 respectively and these pawls are conveniently pivotally supported on a cross bar 72 of the frame by an open ended slot in the arm as indicated at 73 (Fig. 2) in order to facilitate disassembly of the parts without taking the frame apart. This type of construction is utilized in many places, as for instance arm 37' (Fig. 4) is forked upon shaft 29 by the open slot or fork construction as indicated at 75, and arm 36' (Fig. 3) is similarly forked on shaft 29 as indicated at 76.

The gravity pawl 56 is provided with a tail 56' which, when the pawl is moved in the actuating direction and has reached the end of its stroke, comes into such relation with the ratchet wheel, as indicated in dotted lines in Fig. 2, as to prevent overthrow of the ratchet wheel. The pawl 80 is provided to prevent reverse movement 85 of ratchet wheel 39.

I claim as my invention:

1. A perpetual calendar comprising a day dial and its operating ratchet, a month dial and its operating ratchet, a number dial and its operating ratchet, an actuating member, a pair of actuating pawls connected with said actuating member and cooperating with the day dial ratchet and number dial ratchet, blocking means associated with the month dial for determining the stroke of the actuating pawls, other blocking means for normally limiting the actuating movement of the said pawls, means associated with the number dial for retracting said last mentioned blocking means at appropriately spaced intervals, and means for intermittently advancing the first mentioned blocking means.

2. A perpetual calendar comprising a day dial and its operating ratchet, a month dial and its operating ratchet, a number dial and its operating ratchet, an actuating member, a pair of actuating pawls connected with said actuating member and cooperating with the day dial ratchet and number dial ratchet, blocking means associated with the month dial for determining the stroke of the actuating pawls, said means comprising an appropriately notched disk and a finger carried by the month dial, other blocking means for normally limiting the actuating movement of the said pawls, means associated with the number dial for retracting said last mentioned blocking means at appropriately spaced intervals, and means for intermittently advancing the first mentioned blocking means.

3. A perpetual calendar comprising a day dial and its operating ratchet, a month dial and its operating ratchet, a number dial and its operating ratchet, an actuating member, a pair of actuating pawls connected with the actuating member and cooperating with the day dial ratchet and number dial ratchet, a

stop arm arranged to normally limit the stroke of the actuating member, and a cam associated with the number dial for intermittently shifting the stop arm to inactive position.

5. A perpetual calendar comprising a number dial and its operating ratchet, a month dial and its operating ratchet, an actuating member, a pawl connected with said actuating member and cooperating with the number dial ratchet, a stop member arranged to normally limit the stroke of the actuating member, a pawl cooperating with the month dial ratchet, means associated with the number dial for actuating the last mentioned pawl, other cooperating means associated with the number dial and the month dial for retracting the stop member, said other means comprising a pin associated with the number dial and a pawl associated with the month dial, the said pawl cooperating with the stop member when the month dial is in one position.

6. A perpetual calendar comprising a number dial and its operating ratchet, a month dial and its operating ratchet, an actuating member, a pawl connected with said actuating member and cooperating with the number dial ratchet, a pawl cooperating with the month dial ratchet, and means independent of the actuating member associated with the number dial for actuating the last mentioned pawl.

7. A perpetual calendar comprising a number dial and its operating ratchet, a month dial and its operating ratchet, an actuating member, a pawl connected with said actuating member, a stop member arranged to normally limit the stroke of the actuating member and cooperating with the number dial ratchet, a pawl cooperating with the month dial ratchet, means independent of the actuating member associated with the number dial for actuating the last mentioned pawl, and other cooperating means associated with the number dial and the month dial for retracting the stop member.

8. A perpetual calendar comprising a month dial and its operating ratchet, a number dial and its operating ratchet, an actuating member, a pawl carried by the actuating member and acting upon the number dial ratchet, a stroke limiting finger associated with the actuating member, a disk associated with the month dial and having various portions for cooperating with the stroke limiting finger to variably limit the stroke of the actuating member, a pawl acting upon the month dial ratchet, means associated with the number dial ratchet for intermittently actuating said last mentioned pawl, a stop finger for normally limiting the motion of the actuating member, a cam associated with the number dial for intermittently retracting said stop finger, a shiftable

member associated with the month dial for intermittently engaging and retracting the stop member and means associated with the number dial for intermittently shifting said shiftable member to active position.

9. A perpetual calendar comprising a month dial and its operating ratchet, a number dial and its operating ratchet, an actuating member, a pawl carried by the actuating member and acting upon the number dial ratchet, a stroke limiting finger associated with the actuating member, a disk associated with the month dial and having various portions for cooperating with the stroke limiting finger to variably limit the stroke of the actuating member, a pawl acting upon the month dial ratchet, means associated with the number dial ratchet for intermittently actuating said last mentioned pawl, a shiftable member associated with the month dial for intermittently engaging and retracting the stroke limiting finger and means associated with the number dial for intermittently shifting said shifting member to active position.

10. A perpetual calendar comprising a month dial and its operating ratchet, a number dial and its operating ratchet, an actuating member, a pawl carried by the actuating member and acting upon the number dial ratchet, a stroke limiting finger associated with the actuating member, a disk associated with the month dial and having various portions for cooperating with the stroke limiting finger to variably limit the stroke of the actuating member, a pawl acting upon the month dial ratchet, means associated with the number dial ratchet for intermittently actuating said last mentioned pawl, a stop finger for normally limiting the motion of the actuating member, and a cam associated with the number dial for intermittently retracting said stroke limiting finger.

11. A perpetual calendar comprising a day dial and its operating ratchet, a month dial and its operating ratchet mounted on a common shaft, an actuating member, a pair of actuating pawls connected to the actuating member and cooperating with the day dial ratchet and number dial ratchet, a stop member having shoulders variable in height associated with the month dial for controlling the stroke of the actuating pawls, a stop finger for normally limiting the actuating movement of said pawls, and means associated with the number dial for retracting said stop finger at appropriately spaced intervals, and means for intermittently moving said stop member.

12. A perpetual calendar comprising a day dial and its operating ratchet, a month dial and its operating ratchet, a number dial and its operating ratchet, an actuating member,

a pair of pawls connected with said actuating member and cooperating with the day dial ratchet and number dial ratchet, said day dial pawl being arranged to move its ratchet a single step irrespective of the stroke of said pawl, a stop member having shoulders varying in height associated with the month dial for limiting the stroke of the actuating pawls, a stop finger for normally limiting the actuating movement of said pawls, means associated with the num-

ber dial for retracting the stop finger at appropriately spaced intervals and means for intermittently advancing the stop member to bring the different shoulders thereof into block relation with the actuating pawls. 15

In witness whereof I, GEORGE M. DIEHL, have hereunto set my hand at Wabash, Indiana, this 12 day of Dec., A. D. one thousand nine hundred and twenty-one.

GEORGE M. DIEHL.
